[57] **CLAIM**

The ornamental design for hinge for poultry cage gate, as shown and described.

DESCRIPTION

FIG. 1 is a side elevational view of a hinge for poultry cage gate embodying my new design, the opposite side being a mirror image of the side shown;
FIG. 2 is a bottom plan view thereof;
FIG. 3 is a top plan view thereof;
FIG. 4 is a left end elevational view thereof; and
FIG. 5 is a right end elevational view thereof.

FIG. 1

FIG. 4

FIG. 5

FIG. 2

FIG. 3
